GATE HINGE

William F. Grodt, South Gate, Calif., assignor to Arrow-smith Tool & Die Company, a copartnership

Application September 23, 1954, Serial No. 32,403

Term of patent 14 years

(Cl. D10—9)

To all whom it may concern:

Be it known that I, William F. Grodt, a citizen of the United States of America, residing in South Gate, in the county of Los Angeles, State of California, have invented a new, original and ornamental Design for a Gate Hinge, of which the following is a specification, reference being had to the accompanying drawings, forming a part thereof.

Figure 1 is a perspective view of a gate hinge, showing my new design;

Figure 2 is a front elevational view thereof;

Figure 3 is an end elevational view of the left end as shown in the preceding figures; and

Figure 4 is a top plan view thereof.

I claim:

The ornamental design for a gate hinge, substantially as shown.
